US00D632043S

(12) **United States Design Patent**
Rouillard et al.

(10) **Patent No.:** US D632,043 S
(45) **Date of Patent:** ** Feb. 1, 2011

(54) **CLEANING SYSTEM TROLLEY**

(75) Inventors: **Carol A. Rouillard**, Loveland, OH (US);
Andrew M. Bober, Racine, WI (US);
Alfred Adolf Widmer, Wil (CH);
Andrew R. J. Russell, Bourn (GB);
Dave Clark, Welwyn Garden (GB);
Roderick J. McBrien, Leamington Spa (GB)

(73) Assignee: **Diversey, Inc.**, Sturtevant, WI (US)

(**) Term: **14 Years**

(21) Appl. No.: **29/350,837**

(22) Filed: **Nov. 24, 2009**

(51) LOC (9) Cl. **12-02**

(52) U.S. Cl. **D34/21**

(58) Field of Classification Search D34/1-27;
280/47.34, 47.35, 79.2, 79.3, 47.26, 79.5

See application file for complete search history.
